UNITED STATES PATENT OFFICE.

HERMON B. BUTLER, OF CHICAGO, ILLINOIS, ASSIGNOR TO THE JOSEPH T. RYERSON & SONS, OF SAME PLACE.

DESIGN FOR A BOILER-LUG.

SPECIFICATION forming part of Design No. 25,846, dated July 28, 1896.

Application filed June 8, 1896. Serial No. 594,795. Term of patent 14 years.

To all whom it may concern:

Be it known that I, HERMON B. BUTLER, a citizen of the United States, residing at Chicago, Cook county, Illinois, have invented and produced a new and original Design for Boiler-Lugs, reference being had to the accompanying drawings, forming a part hereof.

In the accompanying drawings, Figure 1 is a perspective view of my boiler-lug, and Fig. 2 a perspective front view of the same.

The leading features of my design consist in a main portion forming horizontal projections, depending portions thereon, vertical portions, and a central connecting-piece, the whole resembling somewhat the letter T.

A is the main portion, which consists of two horizontally-projecting portions a a.

B B are the depending portions, C C the vertical portions, and D the central connecting-piece, the horizontal, depending, and vertical projecting portions resembling somewhat the letter T, and the whole presenting to the eye a harmonious and ornate figure, as illustrated in the drawings.

I claim—

The design for a boiler-lug herein shown and described.
